Patented Aug. 7, 1900.

G. A. MOORE.
ACETYLENE GAS LAMP.

(Application filed Nov. 7, 1899.)

(No Model.)

Fig.1.

UNITED STATES PATENT OFFICE.

GEORGE A. MOORE, OF BROMBOROUGH, ENGLAND.

ACETYLENE-GAS LAMP.

SPECIFICATION forming part of Letters Patent No. 655,261, dated August 7, 1900.

Application filed November 7, 1899. Serial No. 736,133. (No model.)

To all whom it may concern:

Be it known that I, GEORGE ARBUTHNOT MOORE, a subject of the Queen of England, and a resident of Bromborough, county of 5 Chester, England, have invented certain new and useful Improvements in Acetylene-Gas Lamps, of which the following is a specification.

This invention has reference to acetylene-gas lamps such as are used for vehicles, for domestic purposes, and the like; and it has more particularly for its object, among others, to provide improvements in such lamps by which the carbid stored in a lamp and not 15 being for the moment used for the making of the gas shall be capable of being stored or held within the lamp or in a part connected with it in such a manner that it will be wholly unaffected by the moisture of or about the 20 lamp and the container or from any source, and consequently will remain absolutely inert and undeteriorated as long as it is not in actual use.

The invention is illustrated in the annexed 25 drawings, in which—

Figure 1 is a sectional elevation showing a lamp provided with the improvements hereunder; and Fig. 2 is a plan in section taken at the line A A, Fig. 1, while Fig. 3 illustrates 30 in section a number of charges of carbid of calcium piled one upon the other and made up according to this invention.

According to this invention the carbid is made up in comparatively-small quantities or 35 charges in suitable proportions to the size of the gas container or vessel, and these charges are so inclosed or wrapped up that while they are within the chamber or reservoir where they are stored no vapor or moisture within 40 the lamp or, in fact, no dampness can reach the carbid; but when they are fed from the container or reservoir (which is effected *seriatim* by suitable mechanical means) and delivered to the place where they are converted 45 to gas by water they cease to be water and damp proof, and access of water to the carbid is provided.

Referring now to the drawings, *a* represents the gas-making chamber of the lamp,

comprising an outer cylinder *a'*, a bottom 50 plate *b*, and a cover or top plate *c*.

d is a tube extending between the cover *c* and the bottom plate *b*, constituting the carbide reservoir or container, this tube being made gas-tight with *c* and *b* where it enters 55 them, and *d'* is a cap on the lower end of the tube *d*, through which the carbide charges are introduced. *e* represents a spring in this tube, which normally is under the carbide charges and forces them upward. 60

f is a carbide-feeding device, it being in the form of a disk disposed in a chamber *g* on the top of the cover *c* and adapted to move charges of carbide from the tube *d* to the chamber *a*. This disk has a chamber *g* within it, 65 while at an equal distance from the center—viz., from the axle *h*—an aperture *c'* is provided in the cover *c*, with which the chamber *g* will coincide when the disk is rotated half a revolution. Over the disk *f* there is a cover 70 or cap *i*, which screws onto the chamber *g* and incloses the whole device, the actuating-spindle *h* alone projecting through this cover.

The lower part of the body *a* is provided with a tube *j*, having a screw-cap *j'*, by means 75 of which the body *a* may be charged with water, and the bottom *b* is provided with a screw-cap *b'*, by taking off which the lime deposit left in the chamber *a* may be removed.

In action assuming the reservoir *d* to have 80 been charged with carbide in the form of a plurality of separate charges and these charges to be pressed upward by the spring *e*, by moving the feeder-disk *f*, so that its chamber *g* is coincident with the upper end of the reservoir *d*, it enables the spring *e* to press the upper end of the pile of charges in *d* up into the chamber *g*, and then by turning the disk around by its operating-handle *h* half a revolution this charge, filling more or less the 85 chamber *g*, will be carried from the reservoir to a point over the opening *c'*, when it will fall from *g* through the opening into the water in *a*, and acetylene gas will be generated. This 90 gas may be burned at the burner *k*, to which it flows from the chamber *a* past regulating or stop valve *l* and a pipe *m*. 95

With regard to the charges of carbide, they

are in one form contained in capsules *o* of suitable material, and these capsules, with their contents, are disposed one upon another, as shown in Fig. 3, and they are all held together 5 and inclosed outside by an envelop *p*, of suitable pliable material impervious to moisture, adhered to the sides of the capsules. The capsules *o* may be made of thin metal or other suitable material inclosing the carbid on the 10 top and at the sides, but not at the bottom; but they are rendered proof against the entry of moisture even at this part also by the envelop *p*. In use a pocket of capsuled charges thus made is placed within the reservoir-tube *d*, and when the feeder-disk *f*, with the chamber *g* standing over the mouth of *d* and the upper capsuled charge within it, is turned by the handle *h* this uppermost charge will be removed, the impervious envelop *p*, of waterproofed paper or other suitable material, being in this action shorn across at the division-line between the two upper capsules, and when this separate capsule falls into the water in the chamber *a* the water 15 has access to the carbid through the open or pervious end of the capsule. The remaining capsuled charges, however, in the reservoir will be impervious to the entrance of moisture, and so on as each charge is removed and fed from the reservoir to the gas-making chamber those remaining are unaffected and proof against the access of moisture to them internally. Hence even if moisture or moist gas does reach the reservoir *d* 20 more or less, this moisture cannot affect the carbid in the capsules, and it remains unacted upon and undeteriorated.

According to a modification, in lieu of the capsules being constructed as just described 40 they may consist of waxed paper or equivalent waterproof material and be practically hermetically closed. In such a case when they are being fed to the lamp gas-making chamber each capsule as it is fed is perforated, so that when they enter the water it 45 can have access to the carbid within. In the lamp shown in Figs. 1 and 2 this puncturing is provided by a pointed punch *r* working in a bearing in the cover *i*, the said 50 punch being disposed over the tube *d*. In action when the upper capsule enters the chamber *g* the punch *r* is pressed down and perforates it, so that when it falls into the water the water has access to the carbid. 55 The capsules in this case may be separate from each other or inclosed in an envelop similarly as shown in Fig. 3. With regard to this feature of the retention of the carbid charges in the reservoir in a condition in 60 which moisture cannot get at them and deteriorate them at all, besides the special method of packing them, the mechanical characteristics of the lamp shown themselves are such that the access of moisture to the

reservoir is extremely small, as the feeding-disk *f* itself forms a valve on the plate or cover *i*, making a gas-tight joint between the gas-making chamber *a* and the reservoir *d*. Hence the escape of gas or moisture from *a* to *d* cannot take place, and the only moisture 70 which has access to it is through the chamber *g*, which will be filled with gas after the feeding action and will carry it from the chamber to the upper end of the reservoir-tube *d*. 75

The reservoir *d* being filled from the lower end, by removing the cap *d'* it is totally out of communication and connection with any portion of the lamp containing moisture.

The amount of carbid contained in each of 80 the capsules *o*—that is, the charges—should be of such size as will fill the chambers *a* with the required volume of gas at a suitable pressure, so that the lamp can be worked for any elected period of time, and the continuous 85 supply of gas is obtained by feeding the charges from the reservoir in which they are stored at intervals, as may be required, to the gas-making chamber.

It is to be stated that the invention is not 90 restricted to the form of lamp and operating mechanism shown in the drawings, as these may be modified or equivalents used without departing from its essential characteristics.

What is claimed in respect of the herein- 95 described invention is—

1. In an acetylene-gas lamp, a lamp-body containing a water and generator chamber, a carbid-reservoir extending longitudinally of said chamber within the same, a transferring 100 device located outside of said chamber and acetylene-reservoir, and within the lamp-body, means for operating the transferring device, means for feeding the carbid thereto and a burner-outlet. 105

2. In an acetylene-gas lamp, a lamp-body containing a water and generator chamber, a carbid-reservoir located within said body, a transferring device located within the body and outside of said generator-chamber and reservoir and having communication with the same, means for operating said device, and a burner-outlet. 110

3. In combination, a cylindrical body having a water and generator chamber within the same, a carbid-reservoir, a transferring device located above said chamber and reservoir and within the body having communication with both the generator-chamber and said reservoir, a stud carrying said transfer 115 device journaled axially of said body, means for turning the stud and a burner. 120

4. In combination in an acetylene-lamp, a body including a cylinder forming the generator-chamber, a second cylinder extending 125 longitudinally of the first within the same, a spring-pressed movable partition in the second cylinder adapted to support a series of

carbid charges, a head to the first cylinder having an opening therein, the upper end of said second cylinder being open and extending through said head, a disk mounted in the body having a recess adapted to align with the opening in the head and the second cylinder, a spindle extending through the head of the lamp carrying the disk, an operating handle on said disk and a piercer guided in

the head of the lamp in alignment with the second cylinder, substantially as described.

In witness whereof I have hereunto set my hand in presence of two witnesses.

GEORGE A. MOORE.
